UNITED STATES PATENT OFFICE.

A. LINCOLN COOMBS, OF CLIFFONDALE, MASSACHUSETTS, ASSIGNOR, BY MESNE ASSIGNMENTS, TO THE SINGER MANUFACTURING COMPANY OF NEW JERSEY.

BUTTON-HOLE SEWING-MACHINE.

SPECIFICATION forming part of Letters Patent No. 389,547, dated September 18, 1888.

Application filed January 16, 1886. Serial No. 188,745. (No model.)

To all whom it may concern:

Be it known that I, A. LINCOLN COOMBS, of Clifftondale, county of Essex, and State of Massachusetts, have invented an Improvement in 5 Sewing-Machines, of which the following description, in connection with the accompanying drawings, is a specification, like letters on the drawings representing like parts.

This invention has for its object to improve 10 that class of button-hole-stitching machines wherein the cloth or other material is carried by a clamp, and the needle-bar, besides reciprocating, is moved laterally to penetrate the material back of the edge of the slit to be 15 stitched and then to descend over the edge, my improvements consisting in providing such class of machines with means whereby the cloth-clamp may be automatically vibrated as the small end of the button-hole slit is reached to be 20 finished, such vibration of the clamp, coupled with the usual motion of the needle, enabling the small end of the slit to be "barred," as it is called, by stitches extended from outside to outside of the stitching covering the side edges 25 of the button-hole slit, and, the barring completed, the machine is automatically stopped.

My invention is herein embodied in connection with a machine having stitch-forming and cloth-clamp-moving scrolls, substantially such 30 as represented in United States Patent No. 123,348, dated February 6, 1872, to which reference may be had.

In accordance with my invention the machine below the bed-plate is provided with a 35 vibrating lever having jointed to it a pawl-carrying slide, upon which is pivoted a pawl which is acted upon by a spring, the normal tendency of the spring being to cause the pawl to engage the teeth of a holding-bar and 40 move it to release a pivoted lever, upon which is mounted a rotating belt-wheel, and let it drop from contact with a friction-pulley fast on the main shaft. The pawl-carrying slide is loosely connected with a slide-bar, one end 45 of which is extended upward through a hole in the bed-plate and placed in such position as to co-operate with a normally-extended arm attached rigidly to the cloth-clamp, the said arm being brought within the range of move-

ment of the said slide-bar as the last side of 50 the button-hole slit is stitched to its end ready to be barred. The inner end of this slide-bar has a finger which controls the time of engagement of the pawl referred to with the holding-bar referred to. The slide-bar is reciprocated uniformly by the vibrating lever while both sides of the slit and its large end are being overstitched; but as soon as the arm of the clamp comes within the range of movement of the slide-bar the latter acts upon the 55 said arm and vibrates the clamp, as will be described, to enable the barring to be done, the number of stitches in the bar being controlled by the number of teeth in the holding-bar, to be described. 60

The particular features in which my invention consist will be herein described, and specifically pointed out in the claims at the end of this specification. 65

Figure 1 is a plan view of the bed-plate of 70 a sewing-machine of the kind referred to, the said figure showing the base part of the usual cloth-clamp with my improved arm attached to it, the figure also showing the devices added by me to vibrate the said clamp, as described, 75 and to operate the releasing-bar, the bed-plate being partially broken out to better show some of the devices below it. Fig. 2 is a section of Fig. 1 in the dotted line *x x*. Fig. 3 is a rear end view of a sewing-machine provided with 80 my improvements, to show the driving mechanism employed with it, said driving mechanism not, however, being of my invention. Fig. 4 is an under side view of the slide-bar, the pawl-carrying slide, the pawl, and part of the lever 85 for moving the same; and Fig. 5 is an under side view of the clamp-base.

The bed-plate A, the upright arm A', the main shaft A³, the friction-pulley A⁴ thereon, the lever D, having the hub 5, the belt-pulley 90 A⁵, mounted on the said hub, the stud D², held by the yoke D', and the upright shaft A², driven from the main shaft A³ by bevel-gears on each, are shown in Fig. 3; but as the said devices are not of my invention they 95 need not be therein specifically described. The shaft A² has fast to it at its lower end the cam C².

The bed-plate A, the cover B, provided with the slot B' to receive the pin 2, carried by the base of the clamp C, and the two scroll-cams B² B⁴ are common to the patent referred to.

The lever D, (see Fig. 3,) has at one end a foot, D⁵, made as a screw, and therefore adjustable with relation to the said lever, the said foot being adapted to bear upon a holding-bar, 44, to keep pressed toward the said holding-bar by a spring, 53.

The lever b³, pivoted to the under side of the bed-plate at b⁴, has a central opening within which acts the cam C², secured to the lower end of the upright shaft A², and vibrates the said lever continuously. The lever b³ has pivoted to its forward end the pawl-carrier slide b⁵, the outer end of which is flanged or turned up to form three sides of a box and 20 constitute a guide, b⁶, for the reception of the inner end of the slide-bar c², the latter having a slot, c³, which is entered by a screw, c⁴. The pawl-carrier has a pawl, b⁷, pivoted upon it at 12, and a spring, 13, acts on the back of the 25 pawl. The pawl-carrier has a lug, 14, in which is placed an adjusting-screw, 15, the turning of the said screw in or out altering the length of the effective stroke of the said slide-bar to accommodate for the length of the bar 30 stitch to be made, that depending upon the size of the button-hole and the class of work being done, the end of the said adjusting-screw acting directly against the end of the said slide-bar.

The slide-bar c², near its inner end, is provided with a pawl-controller, 18, made, as herein shown, of wire and secured to the slide-bar by a screw, 19. The slide-bar c² is normally held with its end extended through the 40 guide 21 and so as to strike against the arm c² as the last side of the button-hole is stitched to its small end. The slot c³ permits lost motion between the slide-bar and the screw c⁴ of the pawl-carrier, and the screw 15 determines 45 how much of this lost motion shall be permitted.

Now, when the pawl-carrier is moved backward or away from the clamp C the screw c⁴, striking one end of the slot c³, draws the slide-bar c² back with it against the spring 17; but as soon as the direction of movement of the lever b³ and pawl-carrier is reversed, should the movement of the slide-bar be checked in the least, so as not to respond to the spring 50 17—as, for instance, by the end of the said slide-bar meeting the arm c²—then the pawl-carrier will have a slight movement while the slide-bar c² and pawl-controller 18 remain at rest, and as a result thereof the pawl is permitted to turn on its pivot and engage one of the teeth 22 at the edge of the holding-bar 44, and the latter bar will be moved by the pawl b⁷ during the remainder of its stroke, and as the pawl so engages the holding-bar the screw 55 15 strikes the end of the slide-bar, and thereafter for the remaining stroke of the pawl-carrier b³ and pawl the slide-bar is moved posi-

tively, and, by its outer end against the arm c², vibrates the clamp C for a short distance about its pin 2 and against the stress of the usual spring, h, which carries the roll h'.

The number of teeth at the edge of the holding-bar 44 equals the maximum number of stitches which it is desired to make to finish or bar the end of the button-hole.

The screw 24 in a lug, 25, of the holding-bar 44 may be turned to adjust the position of the bar and its teeth with relation to the pawl b⁷, so that the whole number of teeth may be engaged one after the other by the said pawl; or the bar may be so adjusted that less than the whole number of teeth may be engaged before the end of the said bar 44, outside the bed-plate A, will be withdrawn from below the foot D⁵ of the lever D, to thereby permit the spring 53 to turn the said lever on the fulcrum-pin D² and cause the removal of the periphery of the pulley A³ from contact with the periphery of the pulley A⁴ and permit the brake-shoe 51, carried by the said lever, to meet the pulley A⁴ and stop the rotation of the needle-bar-moving shaft A².

The screw 24 bears against the screw 26, extended through the slot 27 of the holding-bar, and by turning in the said screw 24 the number of teeth 22 which must be engaged by the pawl b⁷, one after the other, before the holding-bar is pulled from under the foot D⁵ is lessened. The foot, by its friction on the bar 44, prevents movement of the latter except it is positively drawn by the pawl.

The base C of the clamp will be provided with clamping-jaws and devices substantially such as commonly used in the Union button-hole machines or clamping-jaws substantially such as shown in the patent referred to.

The clamp-base C is made to travel in usual manner against the usual needle throat-piece, n, as a guide and to permit the clamp to be moved laterally when occupying the position shown in Fig. 1 by the action of the slide-bar c² against the rigid arm c² of the clamp-base. I have provided the under side of the said clamp-base at one side its straight slot with a slide block or plate, n', fitted into the under side of the clamp-base and flush with its under side, the said block or plate having a slot, n'', which is entered by a pin, n³, in the base.

By means of the block n, the clamp C, when the bar c² meets the arm c², as in Fig. 1, is permitted to move laterally at a point opposite the stationary throat-piece attached to the cover B.

I claim—

1. The clamp-base C, provided with the arm or projection, the slide-bar to co-operate with and vibrate the said clamp, its pawl-controller, and the pawl-carrying slide and its pawl, combined with the bar 44, provided with teeth to be engaged by the said pawl, the number of teeth engaged by the pawl determining the number of stitches made in the barring, substantially as described.

2. The clamp-base C, provided with the arm or projection, the slide-bar to co-operate with and vibrate the said clamp, its pawl-controller, and the pawl-carrying slide and its pawl, combined with the holding-bar provided with a series of teeth to be operated by the said pawl and with means to adjust the range of movement of the said holding-bar according to the number of stitches to be made in barring the end of the button-hole, substantially as described.
3. The clamp C, provided with the arm or projection e^2 , the slide-bar slotted to receive the screw c^4 , and the pawl-carrying slide-bar having a pawl and a lug, and screw 15, to operate against the end of the said slide-bar C²,

combined with a lever to move the said pawl-carrying slide-bar, the adjustment of the screw 15 varying the extent of vibration of the clamp, substantially as described. 20

4. The plate B, its stationary throat, and the clamp-base provided with the loose block or plate n' and the arm e^2 , combined with the slide-bar and means to reciprocate it to vibrate the clamp, substantially as described. 25

In testimony whereof I have signed my name to this specification in the presence of two subscribing witnesses.

A. LINCOLN COOMBS.
